UNITED STATES PATENT OFFICE.

WILLIAM WINGATE, OF BARROW-IN-FURNESS, ENGLAND.

SHIP'S STERN FRAME.

Application filed September 9, 1927, Serial No. 218,467, and in Great Britain November 17, 1926.

This invention relates to the manufacture of ships' stern-frames and its object is to reduce the cost of such manufacture compared with the cost of making stern-frames, as at 5 present, by casting or forging.

According to the present invention, a ship's stern-frame is a compound structure, being wholly or partially built of iron or steel members of roller section secured together by 10 riveting and (or) welding. In some cases the back post only may be built in this manner. Means is provided whereby the compound stern-frame can be secured where necessary to the shell plating of the ship.

15 The members may be iron or steel bars of angle section, channel section, or other section adapted to impart rigidity to the structure. In some cases iron or steel plates may be used and be arranged side by side and 20 secured together to form a laminated structure.

The gudgeons of the back post of the stern-frame are preferably made separately and have extensions which embrace, or fit between 25 or within, the bars or plates constituting the back post, the gudgeons being secured in place by riveting and (or) welding.

The propeller boss may likewise be made separately and have extensions adapted to be 30 inserted between, or within, the bars or plates constituting the propeller-post of the stern-frame and then riveted and (or) welded in place.

The bars or plates forming the stern-frame 35 may be made as a continuous structure, apart from cut-away portions to receive the propeller boss and (or) gudgeons, or, alternatively, the said bars or plates may be made in sections, jointed together by riveting and 40 (or) welding. The joints in the different bars or plates may be made at different places. On the other hand, the stern-frame may be made so that, when desired, the back post 45 may be a separate part and be capable of being shipped into place and unshipped without disturbing the remainder of the frame or its connection to the shell of the ship.

In lieu of constructing the stern-frame wholly of angle or like section bars as afore- 50 said, or wholly of plates arranged side by side, part of the stern-frame may be made accord-

ing to the one construction and another part may be made according to the other construction. In this case, the plates, where necessary, are cut away so as to fit into the channels of the angle or like section bars, and the interengaging parts are held together by rivets or otherwise.

In some cases, the whole or part of the back post may be dispensed with, the stern-frame 60 being then provided with heavy gudgeons on the sole-piece and on an upward extension of the arch of the propeller post for the purpose of carrying the rudder.

In order that the invention may be fully 65 understood, several embodiments thereof are shown, by way of example, in the accompanying drawing, in which:—

Fig. 1 is a side elevation of a preferred construction of stern-frame built of angle-sec- 70 tion bars;

Fig. 2 is a sectional plan taken on the line 2—2 in Fig. 1;

Fig. 3 is an enlarged end view of the joint 75 at the bottom of the stern-frame shown in Fig. 1;

Fig. 4 is a cross-sectional view (enlarged) taken on the line 4—4 (Fig. 1); Figs. 5 and 6 are similar views on the line 5—5 and line 6—6 (Fig. 1) respectively;

Fig. 7 is an end view of the propeller-boss 80 in Fig. 1, looking in the direction of the arrow *w*;

Fig. 8 is an enlarged sectional plan, taken 85 on the line 8—8 (Fig. 1);

Fig. 9 is a side elevation of a modified construction of stern-frame;

Fig. 10 is a sectional plan taken on the line 10—10 (Fig. 9);

Fig. 11 is a cross-sectional view (enlarged) 90 taken on the line 11—11 (Fig. 9);

Fig. 12 is an end view of the propeller boss (Fig. 9), looking in the direction of the arrow *y*;

Fig. 13 illustrates different combinations 95 of angle bars and plates for a stern-frame according to the invention;

Fig. 14 illustrates further combinations of channel bars and plates;

Fig. 15 is an enlarged cross-section of the 100 propeller post of a stern-frame modified for caulking;

- Figs. 16 and 17 are side and plan views of a device for strengthening the parts of the stern-frame;
- Fig. 18 is a side elevation of a stern-frame built of iron or steel plates;
- Fig. 19 is a sectional plan taken on the line 19—19 (Fig. 18);
- Fig. 20 is an end view of the propeller boss shown in Fig. 18;
- Fig. 21 is a side elevation (partly broken away) of a modification of the stern-frame shown in Fig. 18;
- Fig. 22 is an end view of the joint at the bottom of the stern-frame shown in Fig. 21;
- Fig. 23 is a sectional plan taken on the line 23—23 (Fig. 21);
- Fig. 24 is an enlarged cross section on the line 24—24 (Fig. 21);
- Fig. 25 is a cross section of a modification of the construction shown in Fig. 24;
- Fig. 26 is an end view of another propeller boss arrangement;
- Fig. 27 is an enlarged cross section of the propeller-post of the stern-frame shown in Fig. 18 or 21;
- Figs. 28 to 31 are side views of the constituent plates of the laminated stern-frame;
- Fig. 32 is an end view of part of the structure shown in Fig. 28.
- Fig. 33 is a side elevation of a construction of stern-frame in which the back post is dispensed with;
- Fig. 34 is a cross sectional view (enlarged) taken on the line 34—34 (Fig. 33); and Fig. 35 is a similar view taken on the line 35—35 (Fig. 33).
- Referring to Figs. 1 to 8 of the drawings:—
- The stern-frame shown has a back post built of two straight angle-section bars 25 and 26, whose overlapping flanges are secured together by rivets 27, as at Fig. 8. The propeller-post comprises two angle-section bars 28 and 29 likewise secured by rivets 27 (Fig. 7), which bars 28 and 29 are curved at the bottom so as to meet the bars 25 and 26 at right angles, and, at the top, form the arch of the stern-frame, above which a vertical upward extension is provided. To the sides of the bars 28 and 29, margin plates 30, 31 (Fig. 4) are riveted for the purpose of securing the stern-frame to the shell plating of the ship. The sole-piece comprises two angle irons 32, 33 of which the vertical flanges are riveted to the margin plates 30, 31 and to the side flanges of the bars 28, 29, and the horizontal flanges are secured to a rider plate 34, which, along with the said angle irons 32, 33 extends forwardly from the stern-frame and is riveted to the keel 35 of the ship. An additional angle iron 36 is riveted to the rider plate 34 and to the bottom of keel 35 so as to impart greater strength to the joint.
- As will be seen from Fig. 7, the angle-section bars 28 and 29 are expanded outwards from each other and the thwartship flanges
- thereof are reduced in breadth about the middle of the propeller post so that a circular socket is constituted, into which socket a spigot 37 is fitted, this spigot having a flange 38 adapted to bear against the adjacent flanges of the bars 28 and 29 and be riveted thereto.
- In the back post of the stern-frame the gudgeons 39 for the rudder pintles are secured, each gudgeon 39 having a substantially rectangular portion 40 adapted to fit into the channel between the angle section bars 25 and 26 and be held in place by rivets 41.
- The back-post may be so arranged that it can be shipped and unshipped without disturbing the remainder of the stern-frame. According to this arrangement, the margin plates 30, 31 adjacent to the top of the back post are made of such breadth that they embrace the sides of the bars 25 and 26 and also the sides of the bars 28 and 29. By means of rivets 42^a, 42^b the bars 25 and 28 are riveted to the margin plate 30, whilst similar rivets 42^a, 42^b secure the bars 26 and 29 to the margin plate 31. For further security, the overlapping flanges of the angle section bars 25 and 26, and the corresponding flanges of the bars 28 and 29 may be secured together at the top of the back post by the same rivets, instead of by separate sets of rivets as in the remainder of the back post and propeller post. The bottom of the back post is held in place by rivets 43 and 44 (Fig. 3) which are passed through the angle irons 32, 33 on the sole-piece of the stern-frame and, besides penetrating the bars 25, 26 and 28, 29, also pass through the margin plates 30, 31. An angle bracket 28^a (Fig. 1) is fitted into the corner between the bars 25, 26 and 28, 29, and is secured thereto by riveting or welding. It will thus be clear that to unship the back post only the rivets 42^a, 43 and 44 and the said angle bracket 28^a need be removed.
- Referring now to the arrangement shown in Figs. 9 to 17:—
- In this case, instead of using two angle-section bars 25, 26 or 28, 29 with overlapping flanges as hereinbefore described, I may use two angle section bars 45, 46 (Fig. 13) with their flanges abutting and connected together by a separate strip 47, or a single channel section bar 48 (Fig. 13) may be used. Alternatively, if greater strength is necessary, two or more channel section bars 48 (Fig. 14) may be used, in which case the two bars may be set with their channels facing towards or away from each other, or both facing in the same direction. Where two or more channel section bars are employed, they may be held together by side strips 49, serving also as margin plates aforesaid, or if the bars are back to back they can be secured to each other, either with or without an intermediate distance piece. Instead of using a pair of chan-

nel section bars, single bars of H section or box section can be used.

In Figs. 9 to 12, I have shown a stern-frame built of angle section bars 45 and 46 connected together by a strip 47 and provided at the sides with margin plates 30 and 31. This frame is made as a continuous structure throughout except at the propeller boss, where the bars 45 and 46 and strip 47 are cut away and the margin plates 30, 31 are expanded outwards from each other to form a substantially circular socket. The propeller boss 37^a comprises a ring portion formed with a pair of diametrically opposite lugs 50, these lugs being so shaped that, when the ring portion of the boss is fitted into the circular socket of the propeller post, the lugs 50 project upwards and downwards into the channels between the angle section bars 45 and 46, small shoulders 51 being also formed on these lugs to bear against the abutting ends of the said bars. The boss 37^a is secured in position by rivets 52 passed through the side flanges of the bars 45, 46 and the lugs 50 of the boss.

The attachment of the gudgeons 39 to the angle section bars 45 and 46 is effected by rivets 41 in substantially the same manner as described with reference to Figs. 1 and 8.

The frame formed by the angle section bars 45, 46 is connected to the keel of the ship, firstly by a rider plate 53 (see Fig. 11), to which the horizontal flanges of the bars 45, 46 are riveted, and, secondly, by two angle irons 54, 55 whose vertical flanges are riveted to the margin plates 30, 31 and the side flanges of the bars 45, 46.

In the modification shown in Fig. 9 the abutting parts of the propeller post and back post are jointed by an angle bracket 56 through which rivets 57 are passed into the connecting strip 47 and adjacent flanges of the bars 45 and 46.

To enable the joints between the aforesaid bars or plates to be readily caulked, such joints are arranged so that an upstanding face is provided, along the edge of which the caulking tool can be applied. Thus, in Fig. 15, the angle section bars 28 and 29 of the stern-frame illustrated in Fig. 1 are shown adapted for caulking, the end of the flange 28^a of the bar 28 terminating a short distance away from the interior corner of the bar 29, and likewise the end of the flange 29^a of the bar 29 terminating a short distance away from the corner of the bar 28, whilst the margin plates 30, 31 for the same purpose are terminated a short distance away from the corners of their respective angle bars 28 and 29.

For strengthening purposes, a number of transverse ribs such as 58 (Figs. 16 and 17) may be applied to the bars of the stern-frame throughout. The said rib 58 is formed with vertical flanges 59 adapted to be secured to the flanges of the bars 28 and 29 by rivets 60. Al-

ternatively, the ribs 58 may be secured in place by welding and the flanges 59 dispensed with.

Referring to the construction shown at Figs. 18 to 32 of the drawings:—

The stern-frame illustrated on these figures is built of comparatively thin steel plates cut to the required size and shape, there being five plates in all (Fig. 27), the two outermost plates 61, 65 being thicker than the three inner plates 62, 63 and 64. The outermost plates 61 and 65, are similar and are as shown in side elevation in Fig. 28; from which it will be seen that each of the said plates is made up of six sections connected by scarf joints indicated at 66. The intermediate plate 62 (Fig. 29) consists of four sections connected by scarf joints indicated at 68, whilst the intermediate plate 64 (Fig. 31) consists of four sections connected by scarf joints 69. The scarf joints are located so that a joint does not occur in all the plates at the same place. In the case of the plates 62 and 64, the scarf joint at the juncture of the arch and back post extension is reinforced by welding 70. It will be seen from Figs. 29 to 31 that portions of the plates 62, 63 and 64 are cut away to accommodate the propeller boss (see also Fig. 20).

Figs. 18 to 21 illustrate the plates 61 and 65 arranged side by side and secured together by rivets 71 so as to form a laminated stern-frame, the rivets 71 also serving to hold in place the margin plates 30 and 31 (see also Fig. 27). The seams between the plates may be closed by electric or other welding operation. The sole piece of the laminated frame is provided with two straps 72 for strengthening purposes.

A modification of the laminated stern-frame above described is shown in Figs. 21 to 23, the plates 61 to 65 in this modification being made so that the back post as a whole can be shipped and unshipped without disturbing the remainder of the frame. As in the modification described with reference to Fig. 1, the margin plates 30 and 31 are made of greater breadth at the top of the stern-frame so as to embrace the sides of both the back post and upward extension of the propeller post. The back post and said upward extension are secured to the margin plates 30, 31 by elongated rivets 71. The lower end of the back post is adapted to fit into the rear end of the sole piece by making the alternate plates 61, 63 and 65 in the sole piece overlap the intermediate plates 62 and 64 in the back post, and riveting the interengaging parts together. Thus the back post can be unshipped simply by removing the rivets connecting it to the margin plates 30, 31 and overlapping plates 61, 63, 65 of the sole piece.

As will be apparent from Figs. 24 and 25, the gudgeons 39 may have extensions 73 which embrace the back post and are held in place by elongated rivets 71 or may have a single

extension 75 which fits between the outer plates 61 and 65, the middle plate 63 and intermediate plates 62 and 64 being cut away for this purpose.

5 The propeller boss 76 (Fig. 20) has two stepped extensions 78, 79 adapted to be inserted between the plates 61 and 65 and then riveted in place. At the propeller boss, the margin plates 30, 31 are cut away and the intervening space is bridged by curved plates 81.

A modified form of propeller boss is shown in Fig. 26, the outer plates 61 and 65 in this case not being carried round the boss, but being cut away a short distance beyond the ends 15 of the plates 62, 63 and 64, and the boss being shaped to correspond. As in the aforementioned modification, curved plates 81 are provided between the parts of the margin plates 30, 31.

20 It will be apparent that, whilst the invention has been described with reference to a stern-frame having a propeller post and back post separated by an aperture as for a single screw ship, it is equally applicable to the constitution of stern-frames of L-shape (generally termed stern-posts) for twin, or quadruple, screw ships and paddle steamers.

In this modification, the stern-post may comprise a pair of angle section bars formed 30 into the desired L-shape, the bars being fitted together so as to form a compound channel bar, and being secured to each other by rivets passed through their overlapping flanges. Margin plates for the shell plating are secured to the side flanges of the bars and gudgeons are fitted thereto for the reception of the rudder pintles, in substantially the same manner as hereinbefore described with reference to the stern-frame 40 shown in Figs. 1 and 8. Likewise, the stern-post extends upward to the transom floor and is secured thereto by angle brackets. The sole piece of the stern-post comprises angle irons whose upright flanges are riveted to 45 the side flanges and margin plates of the compound bar and whose horizontal flanges carry a rider plate. Stern-posts may also be made of other angular, channel and like section, or may be made of laminated form, 55 the plates in this case being cut to the proper shape, then placed side by side, and riveted together.

Referring to Figs. 33 to 35:—

In this modification, the whole of the back 55 post is dispensed with, but the construction of the stern frame, in other respects, is similar to the construction described with reference to Figs. 1 to 8. The sole-piece of the frame, however, is provided with a foot-step 60 gudgeon 82, and the upward extension of the propeller post carries a heavy gudgeon 83. As shown in the sectional plan (Fig. 34), the gudgeon 83 is formed with rearwardly projecting jaws 84 adapted to embrace the 65 sides of the angle section bars 28 and 29. In

order that these bars may provide a firmer support for the gudgeon 83, a distance piece 85 is inserted between the side flanges of the said bars, and the gudgeon is held in place by rivets 86 which are passed through the 70 jaws 84, distance piece 85 and the side flanges of the bars 28, 29. The sectional end view shown in Fig. 35 illustrates the mounting of the footstep gudgeon 82. The lower portion of this gudgeon is extended downwards to 75 constitute a saddle-piece comprising side flanges 87, 88 connected by an end flange 89 (Fig. 33). By means of this saddle piece, the gudgeon 82 is adapted to rest on the rearwardly projecting ends of the bars 32, 33 80 and 28, 29. The said gudgeon is secured in this position by means of rivets 90, 91, which are made slightly longer than the rivets 43, 44 serving to hold the bars 32, 33 and 28, 29 together. 85

It will be understood that the bearing surfaces provided in the gudgeons 82 and 83 may be of any known design suitable for the purpose.

The elimination of the back post or part 90 thereof results in a lighter stern-frame, without reducing disadvantageously the strength of the frame.

It is to be understood that within the term "iron or steel members of rolled section" 95 as herein used, I include all rolled iron or steel members such as bars of angle, channel or annular section, or flat plates.

It is also to be understood that, in stern-frames made in accordance with my invention, the exterior of the propeller boss, besides being circular may be of rhomboidal or other polygonal shape. 100

Further modifications may be made in my invention, without departing from the scope 105 thereof, and the shape of the parts can be varied to suit different sizes and types of ships.

I claim:—

1. A ship's stern-frame comprising a back 110 post; a propeller post structure built of iron or steel members of rolled section; a sole plate built of iron or steel members of rolled section; flange members separate from but overlapping the parts of said structure and sole 115 plate adjacent to the ship's shell plating; means connecting the overlapping parts of said flange members to said structure and sole plate; and means securing the members of said structure and of sole plate to one another. 120

2. A ship's stern-frame comprising a back post built of angle-section members; a propeller post structure built of angle-section members; a sole plate built of angle section members; margin plates overlapping the parts of said structure and sole plate adjacent to the ship's shell plating; means connecting the overlapping parts of said margin plates to said structure and sole plate; and 130

means securing the members of said structure and sole plate to one another.

3. A ship's stern-frame comprising a back post; a propeller post structure built of iron or steel members of rolled section; a sole plate built of iron or steel members of rolled section; flange members overlapping the sides of said structure, sole plate and back post adjacent to the ship's shell plating;

rivets connecting said flange members to said structure, sole plate and back post; rivets connecting the rolled section members of said structure and of said sole plate to one another; and means connecting said back post to said structure and sole plate detachably. 10 15

In testimony whereof I affix my signature.

WILLIAM WINGATE.
